UNITED STATES PATENT OFFICE.

RUSSEL G. WOODWARD, OF WAUKEGAN, ILLINOIS, ASSIGNOR TO UNION SPECIAL SEWING MACHINE COMPANY, OF CHICAGO, ILLINOIS, A CORPORATION OF ILLINOIS.

THREAD-CONTROLLING DEVICE FOR SEWING-MACHINES.

1,072,291.

Specification of Letters Patent.

Patented Sept. 2, 1913.

Application filed April 9, 1903. Serial No. 151,825.

To all whom it may concern:

Be it known that I, RUSSEL G. Woodward, a citizen of the United States, residing at Waukegan, in the county of Lake, 5 State of Illinois, have invented certain new and useful Improvements in Thread-Controlling Devices for Sewing-Machines, of which the following is a description, reference being had to the accompanying drawing and to the letters and figures of reference 10 marked thereon.

My invention relates to an improvement in thread controlling devices for sewing machines and particularly to a pull off and 15 take up device for the looper thread, on double chain stitch machines.

The object of the invention is to provide an improved thread controlling device and 20 particularly an arrangement for giving and taking up slack, the slack occurring when the looper begins to move forward and the thread remaining slack until it reaches the end of its forward movement. The slack is taken up as the looper moves backward 25 and the needle descends until it has entered the loop properly and then the slack again occurs, while the looper is moving toward the extremity of its backward throw, while the needle is pulling up the previous stitch 30 and allows the needle thread to have freedom in going up and at the same time allows the looper thread to be carried up to the goods freely, giving the upper thread full control over the lower thread.

This invention has been designed especially for use upon machines for making very fine stitches, such machine having a variable looper movement with a short throw, substantially as shown in the application 40 filed by Lansing Onderdonk, November 9th, 1901, Serial No. 81,760 patented December 31st, 1907, No. 875,671. In making long stitches upon a machine of this character, a take up for the lower thread is 45 not absolutely necessary, as the looper pulls off its own thread and takes up its own slack, but in some kinds of work, as for example, in the sewing of silk gloves, a very fine stitch must be made, and this in-

vention is of particular value in machines of this character.

The invention consists in the various matters hereinafter described and referred to in the appended claims.

The invention is illustrated in the accompanying drawing, in which—

Figure 1 is a front elevation, with the bed plate removed, of a sewing machine embodying the invention; Fig. 2 is a skeletonized view showing the relation of the parts when the needle is at its lowest point and the looper at the extremity of its backward stroke; Fig. 3 is a view similar to Fig. 2 showing the relation of the parts with the looper moving backward and the needle 60 moving down, when the take up is about to cast off the thread; Fig. 4 is a view similar to Fig. 2 with the looper at the forward end of the stroke and the needle at its highest point; Fig. 5 is a detail sectional view 65 of the take up and cast off mechanism, and Fig. 6 is a sectional view on line 6—6 of Fig. 4.

In these drawings the machine shown is of the well known Union Special single needle, double chain stitch type with the trimmer and having a looper with a variable movement imparted to it by connections between the end of the looper rod and the needle lever extension, whereby a short 75 looper having a short throw may be used, substantially as is set forth in the application of Onderdonk above referred to.

A represents the bed of the machine, B the goose neck, C the head thereof, D the needle bar, a the needle, E the looper rocker, b the looper, F the looper rod, G the needle lever, H the trimmer. The looper rod F is attached to the crank e pivoted to the short stud d on the machine frame. Pivoted to the crank e is a link f pivoted to the lower end of the needle lever extension g. By this arrangement a quick movement into and out of the needle loop is given to the looper, and a short looper with a short throw 90 may be used.

Attached to the standard of the machine is a bracket plate 1, carrying on its outer

end a casing 2, in which is suitably arranged a plate 3, carrying two arms 4 having eyelets and carrying also a cast off plate 5. This plate 3 has a screw threaded lug within the casing and a screw 6 acts to adjust the eyelet arms and cast off plate vertically.

Upon the driving shaft S near its rear end, is an eccentric 7 embraced by an arm 8 which, at its rear end, is slidably pivoted 10 on the bracket 9 attached to the bed of the machine. This carries at its front end take up fingers 10, which oscillate in a plane between the eyelet arms 4 and upon either side the cast off plate 5 and have shoulders 11 15 engaging the thread which runs between the eyelet arms, carrying the thread upwardly and rearwardly, until the plate 5 operates to cast off the thread from the shoulders.

Thread guides 12, 12 are arranged upon 20 the needle lever extension which act in the backward oscillation of said needle lever extension, while the needle is going down, to pull off thread from the spools through the tension 13. The stud 14 on the crank c, 25 to which looper rod F is attached, has a grooved collar or washer 15 thereon, which acts as a guide for the thread which is led over it and under a wire 16 on the frame of the machine, to the eyelet arm 4.

30 The manner of threading the looper is as follows: The thread is led from the spool to the lower tension 13 on the front face of the overhanging frame, to the thread guides 12, on the lower end of the needle lever extension, over the ball joint collar or washer 15, under the wire 16 to the eyes on the adjustable arms 4 on the right and left hand side of the take up and cast off, thence to the heel of the looper and to the eye thereof.

40 In operation the take up and pull off devices work as follows: Assuming the needle to be in its lowest position and about starting up to throw out a loop, the take up shoulders are not acting on the thread but are on their downward movement, but as the looper goes forward and the crank carrying the collar 15 over which the thread is guided, moves downwardly, it gives slack thread to the looper faster than the looper travels and consequently the thread is slack from the starting of the looper forward until it reaches the end of its forward movement, but by reason of the course the thread takes over said collar 15 and under the wire 16, the thread will not be entirely slack so as to sag, but at the limit of its forward movement, will become fully slack. Just as the needle moves down and the looper begins to move back, the take up shoulders

50 engage the thread and take up the slack in order that the needle may enter the loop properly, holding the thread until the needle has gone into the loop, when the cast off acts and lets the thread become slack again. On the upward movement of the

arm carrying the collar 15, the looper thread is taken up gradually, and thus takes the slack out of the looper thread which is given up to the looper as it moves forward. This prevents the thread from getting around the point of the looper, which would be the case if the looper thread is allowed to remain slack at the end of its return stroke. The movement of the extension of the needle lever away from the looper will not disturb the thread between the swinging arm and the looper, for the reason that more or less friction is placed on the looper thread by the collar, the thread guide and the shoulders of the take-up, which prevents the drawing of the thread backward by this movement of the needle lever extension.

Another advantage of handling the thread in a slack condition, as set forth, is that it avoids the wear of the eyes in the looper, which is a rather serious objection. In the machines as usually constructed, when the looper thread is drawn taut and handled in this condition, the eyes of the looper wear through or form grooves in the ends of the 90 eyes, which is apt to cause breakage of the thread if there is an uneven surface in said thread.

Having thus described my invention, what I claim and desire to secure by Letters Patent, is:—

1. In a sewing machine, stitch-forming mechanism including a needle and a looper co-operating therewith to form stitches, a device operating upon the looper thread and giving slack thereto as the looper moves forward, and a second device operating upon the looper thread while the looper is moving backward to take up the slack in the looper thread and release the thread after the needle has entered the looper thread loop, said first named device operating to take up the looper thread after it has been released by said second device.

2. In a sewing machine, stitch-forming mechanism including a needle, and a variably speeded looper co-operating therewith to form stitches, a controller for the lower thread comprising devices for giving slack thread to the looper as it moves forward, and a full slack thread when the looper is at the end of its forward movement, a take-up operating to take up the slack thread while looper is moving backward and a cast-off for casting said thread from the take-up after the needle has entered the looper loop, said controller operated to gradually take up the slack after the thread is cast off the take-up.

3. In a sewing machine, stitch forming mechanism including a needle, and a variably speeded looper co-operating therewith to form stitches, a controlling device for the lower thread, comprising a take up member to engage the thread and take up the slack

on the backward movement of the looper, a cast off coöperating therewith and operating to give a slack thread after the needle has entered the looper loop, and devices for controlling the slack while the looper is completing its backward movement; substantially as described.

4. In a sewing machine, stitch forming mechanism, including a needle, a variably speeded looper coöperating therewith to form stitches, a controlling device for the looper thread comprising a take-up member to engage the thread and take up the slack, a cast-off coöperating therewith and operating to give slack thread to the looper after the needle has entered the looper thread loop, means for controlling the slack in the looper thread after it has been released by the cast-off, including a thread engaging device and a thread eye, and movable thread guides through which the thread passes from the supply to the slack thread controller and take-up member.

5. In a sewing machine, stitch forming mechanism including a needle, and a looper coöperating therewith to form stitches, stationary guides for the thread, take up member reciprocating in a plane between the guides and operating in one movement of the looper, a cast off plate coöperating with said take up member, a slack controlling device operating upon the thread and comprising a swinging arm over which the thread is guided to give slack as the looper moves forward and gradually take up the slack in the reverse movement, and a stationary guiding wire under which the thread is guided, and a pull off; substantially as described.

6. In a sewing machine, stitch forming mechanism including a needle, and a looper coöperating therewith to form stitches, stationary guides for the thread, take up member reciprocating in a plane between the guides and operating in one movement of the looper, a cast off plate coöperating with said take up member, a slack controlling device operating upon the thread and comprising a swinging arm over which the thread is guided, and a stationary guiding wire under which the thread is guided, and a pull off carried by the needle lever, and connections between the needle lever and the swinging arm, whereby the latter is operated; substantially as described.

55 7. In a sewing machine, stitch forming mechanism including a needle and a looper coöperating therewith to form stitches, a thread controller, comprising devices for giving slack thread to the looper faster than the looper travels in its forward movement, giving a full slack thread when the looper is at the end of its forward movement, a take up, timed to take up the slack when the looper begins to recede and to hold it taut until the needle has entered the loop,

a cast off for giving slack after the needle has entered the loop and devices for gradually taking up the slack while the looper is passing to its extreme backward position; substantially as described.

70

8. In a take-up device of the character described, stationary guiding arms for the thread carried on a suitable support, a cast-off plate also carried by said support, and means for adjusting said plate and guiding arms simultaneously; and a thread-controlling device arranged to coöperate with the guiding arms and cast off plate substantially as described.

75

9. In a sewing machine, stitch-forming mechanism including a needle, a looper coöperating therewith to form stitches, a movable member, slack-controlling devices including a swinging arm over which the thread is guided, a stationary guiding wire under which said thread is guided, thread guides carried by the movable member, and connections between the latter and the swinging arm, said stationary guiding wire being so disposed relative to said swinging arm that slack thread is given up during the entire forward movement of the looper.

80

10. In a sewing machine stitch-forming mechanism including a needle, a looper coöperating therewith to form stitches, slack-controlling devices including a swinging arm over which the thread is guided, a stationary thread guide through which said thread is guided on its way to the looper from said swinging arm, and means for operating said swinging arm, said stationary guide being so disposed relative to said swinging arm that slack thread is given up during the entire forward movement of the looper, and a take-up and cast-off mechanism for engaging the looper thread between the swinging arm and the looper.

95

11. In a sewing machine, the combination of a stitch-forming mechanism including a needle and a looper, a needle lever, a needle lever extension carried thereby, a thread guide located on said needle lever extension, a swinging arm operatively connected with the needle lever extension and moved thereby, a guiding device carried by said arm over which the thread is guided from the needle lever extension to the looper, and a stationary thread guide secured to the stationary part of the machine frame between the swinging arm and the looper and under which the thread is guided.

100

12. In a sewing machine, stitch-forming mechanism including a needle and a looper coöperating therewith to form stitches, a needle lever having an extension, a thread guide located on the needle lever extension, a swinging arm operatively connected with the needle lever extension, and provided with a guiding device over which the thread is guided, a thread guide secured to a sta-

125

- tional part of the machine frame, and under which the thread is guided, and a take-up and cast-off mechanism; substantially as described.
- 5 13. In a take-up device of the character described, stationary guiding arms for the thread carried on a suitable support, a cast-off plate also carried by said support, means for adjusting said plate and guiding arms simultaneously and a take-up member co-operating therewith; substantially as described.
- In testimony whereof I affix my signature, in presence of two witnesses.

RUSSEL G. WOODWARD.
